UNITED STATES PATENT OFFICE.

LEO CHANIN, OF BROOKLYN, NEW YORK.

GARTER SOCK.

Application filed September 28, 1923. Serial No. 665,425.

To all whom it may concern:

Be it known that I, LEO CHANIN, a citizen of the United States, and a resident of the city of New York, borough of Brooklyn, in the county of Kings and State of New York, have invented a new and Improved Garter Sock, of which the following is a full, clear, and exact description.

This invention relates to a garter sock, and has for an object the provision of a combination sock and garter whereby the support of the sock from the garter is rendered much more efficient and uniform so that the sock is properly suspended and will wear a considerably longer time.

Another object is to provide a garter sock in which the portion embracing the calf of the leg is constructed to effect such embrace in a new and improved manner whereby the discomfort of the present type of embrace is eliminated.

The invention is illustrated in the drawings, of which—

Figure 1 is a perspective view of a leg showing the garter sock applied thereto;

Fig. 2 is an enlarged perspective of the upper end of the sock and garter;

Fig. 3 is a vertical section taken through the upper end of the garter taken on the line 3—3 of Fig. 4; and

Fig. 4 is a partial side elevation of the device.

The form of the invention shown in the drawings is a preferred form, although it is understood that modifications in the construction and arrangement of the parts and in the character of the materials used may be adopted without departing from the spirit of the invention as set forth in the appended claims.

The invention as shown in the drawings is applicable to a sock 1, of which the foot portion 2 is knitted with a reinforcing portion along the entire foot. This reinforcing portion extends upwardly on each side of the foot and leg of the sock as a narrow band of material 3 which passes up through the upper reinforced edge 4 of the sock and extends above this portion to form a narrow band of doubly reinforced material 5 which is bent back in the form of a loop

and is rendered adjustable by means of the use of an adjusting plate 6 of any well known type, so that the length of the band 5 above the top of the garter can be regulated. The upper end of this loop portion of the band 5 is adapted to be associated with a band 7 of similar material encircling the calf of the leg, the ends of this band 7 being adjustably connectable by any suitable means, such as 8. This band is provided with a metal loop 9 with which the upper end of the fabric loop 5 engages. It is, of course, understood that there is a loop of the nature of 5 extending forward on each side of the leg, as shown in Fig. 2.

As shown in Fig. 4, it will be observed that the band 7 is arranged at a decided angle with respect to the band or strip 5, and this angular arrangement is for the purpose of providing more effective grip of the band on the calf of the leg, a grip more in accordance with the natural shape and slope of the calf, so that a sufficient grip is obtained without having to fasten the band so tightly as to be uncomfortable to the wearer.

It will, therefore, be observed that I have provided a sock so constructed with reenforced portions that the leg-encircling band connected to integral parts of the sock will pull upwardly on the sock, not at any one particular point but throughout its entire construction, and that the pull is braced, through the reenforcing portions, along the entire bottom of the sock, whereby this kind of pull does not tend to grip or tear the sock and holds it up much more uniformly than at present is possible.

What I claim is:—

1. A garter sock which includes a knitted reenforcing portion extending over the foot of the sock, and strips of reenforcing material extending upward on each side of the sock from said reenforced foot portion, said strips of reenforcing material extending upwardly above the top of the sock.

2. A garter sock which includes a knitted reenforcing portion extending over the foot of the sock, strips of reenforcing material extending upward on each side of the sock from said reenforced foot portion, said

strips of reenforcing material extending upwardly above the top of the sock, said strips above the top of the sock being formed in loops, and adjusting means connected to said loops whereby the length of said strips above the top of the sock can be regulated.

3. A garter sock which includes a band of knitted fabric for encircling the calf of the leg at an angle to the horizontal, a sock,

and a knitted band of material formed integrally in the body of the sock extending upwardly from the upper edge thereof and engageable with said leg-encircling band, the upper ends of the bands extending from the sock being formed in loops and adjustable.

LEO CHANIN.
